MANUFACTURE OF CARTONS

John Hoza, Zlin, Czechoslovakia

Application May 31, 1938, Serial No. 210,974
In Czechoslovakia May 13, 1937

8 Claims. (Cl. 93—51)

This invention relates to the manufacture of cartons, by which expression is meant light boxes made from a blank of thick paper or light board (for example, paste-board) which blank is foldable into the form of a box and maintainable by affixation means in that form.

An object of the invention is to provide a method of manufacture by virtue of which one can avoid manual operations, increase the rate 10 of output and thus lower the cost of production.

Another object of the invention is to provide a method of manufacture by virtue of which the carton components will be adhesively bound to one another with permanent and uniformly distributed firmness, in contradistinction to known cartons whose components are held together by staples at single points spaced apart.

Another object of the invention is to provide a method of reinforcing the cartons produced at 20 their marginal edges and preferably also at their corners.

Another object of the invention is to provide a machine which will be capable of carrying out the method of manufacture of cartons and which 25 will be automatic in its action.

Other objects of the invention will be evident from the following specification and claims.

The invention will now be described by way of example with reference to the accompanying 30 drawings, in which:

Fig. 1 is a transverse section of an automatic machine for the manufacture of cartons and Fig. 1a is a corresponding longitudinal section. Figs. 1 and 1a illustrate an initial stage in the cycle 35 of operations of the machine.

Figs. 2 and 2a, Figs. 3 and 3a, Figs. 4 and 4a, Figs. 5 and 5a and Figs. 6 and 6a are pairs of views similar to Figs. 1 and 1a but illustrating successive stages in the cycle of operations.

Fig. 7 is a plan of the blank from which a 40 carton is made.

Fig. 8 is a fragmentary perspective view showing the blank with one side wall portion raised, said portion having previously had its margin doubled back, and with a lateral extension of 45 said portion inturned.

The manufacture is performed in the following manner:

A blank, i. e. the stamped-out paper (see Fig. 50 7), from which each carton is formed is initially stamped out by automatic stamping mechanism and if desired is simultaneously impressed with suitable printing or other matter, and by means of further mechanism (the bending mechanism) 55 doubling-back of the marginal portions C, D on

the longitudinal side wall portions J, K of the blank is effected, and the blank thus prepared reaches the actual folding and binding machine.

In the entry of the prepared blank to the machine, it passes through a feed-in device and an adhesive-applying device, which latter applies adhesive to the blank on the end wall portions A, B and the marginal portions N, O projecting from the portions A, B, and the blank is led to the actual folding and binding machine now to be 10 described.

The feed-in mechanism brings the blank 1 under the ram or pressure-head 6 into the position defined by the stop 5, and at the sides the blank is guided by the guides 3, 4, the parts 3, 4 15 and 5 being on a longitudinal ledge 7, 8 presenting a supporting surface for the blank above a matrix 6' with which the ram co-operates. Figs. 1 and 1a illustrate the blank in its uppermost position under the momentarily stationary ram 20

6. The ram 6 which is provided on a yoke (not shown in the drawings) and co-operates with the matrix, is actuated by a cam-device (also not shown) which moves it up and down at definite periods in the cycle of operations timed by the 25

6. The ram 6 which is provided on a yoke (not shown in the drawings) and co-operates with the matrix, is actuated by a cam-device (also not shown) which moves it up and down at definite periods in the cycle of operations timed by the 25

6. The ram 6 which is provided on a yoke (not shown in the drawings) and co-operates with the matrix, is actuated by a cam-device (also not shown) which moves it up and down at definite periods in the cycle of operations timed by the 25

6. The ram 6 which is provided on a yoke (not shown in the drawings) and co-operates with the matrix, is actuated by a cam-device (also not shown) which moves it up and down at definite periods in the cycle of operations timed by the 25

In the continued descent of the ram, bending 45 ledges in the form of narrow plates 12 arranged at the side faces of the matrix, bend the adhesive-coated walls A, B, of the blank upwardly and press them against the inturned extensions or inserts E, F, G, H, as will be apparent from 50 Figs. 4 and 4a.

The carton, already partially formed in the manner stated, in the continued descent of the ram 6, continues to be depressed and is forced past plates 12 until the stiffening marginal por- 55

tions N, O, now at the tops of the end walls A, B, reach the plane of displaceable bending ledges or plates 14. At this moment, the bending ledges 14 are set in motion inwardly and bend the marginal portions N, O into the interior of the carton in a direction perpendicular to the end walls A, B, the portions N, O ultimately extending over the inserts E, F, G, H, as will be apparent from Figs. 5 and 5a.

10 The bending ledges 14 also are actuated by cam mechanism which is driven through a yoke in operative connection with the cam that operates the ram 6, the cams for driving the ram 6 and for the ledges 14 thus receiving positively related movements.

15 A further stage in the manufacture of the carton consists in doubling-down the marginal portions N and O against the side walls J, K. This doubling-back is effected by slides 15, 16 which are arranged directly on the ram 6. These slides are operated by two-armed levers 17 which are fulcrumed in the ram and are operable under the control of cam-mechanism including a rod 2. The cam-mechanism is so timed that, at the 20 end of the descent of the ram, the levers 17 simultaneously constrained to pivot and force down the slides 15, 16. Thus, in the lowest position of the carton, the marginal portions N, O are doubled-down and press against the end walls 25 A and B, the inserts E, F, G, H, and corner reinforcements constituted by lateral projections C¹, D¹ of the marginal portions C, D.

30 The carton is now finished to such an extent that only the final pressing of the adhesive-coated portions has to be effected, this operation being effected in the lowest position of the ram by cam-operated pressure plates 11, 13 (see Figs. 6 and 6a). After the pressure operation, the upward movement of the ram 6 occurs and this 35 movement completes one cycle of operations of the machine.

35 It is necessary that in the ascent of the ram, it shall not take with it the carton, which tends to stick to it. Accordingly means are provided 40 to hold the carton fast; and such means may for example be springs (not shown in the drawings). Thus, the carton remains in the position corresponding to the lowermost position of the ram.

45 Thereupon, the entire cycle of operations is 50 repeated for the next blank, and the second carton when completed ejects the first carton out of the matrix. The cycle can be repeated continuously, without interruption of the operation of the machine. The completed cartons are 55 ejected from the matrix upon a conveyor band, which conveys them to their place of use.

60 It will be clear that the doubled-down marginal portions C, D, N and O of the respective walls give the walls stiffened tops, which add greatly to the strength of the carton, and that the corner reinforcements C¹, D¹ add still further to the carton's strength.

65 The machine hereinbefore described can be altered as regards various constructional details without thereby departing from the scope of the invention.

70 In the following claims, reference is made to "side" wall portions and "end" wall portions of the blank and to "side" walls and "end" walls 75 of the carton. It is to be understood that the terms "side" and "end" are used purely for simplicity and clarity of definition and are not intended to be limitative as regards the relative dimensions of the parts concerned, and it is to be understood that the "end" dimension may be

shorter or longer or the same as the "side" dimension.

I claim:

1. A method of manufacturing a carton from a blank, said blank including as components wall portions, lateral extensions on certain of said wall portions and projecting margins on certain of said wall portions, certain of said components being treated with adhesive, which method consists in leading-in the blank as one of a series of blanks from an adhesive-treatment station to a matrix at a forming station, seating the blank in position above the matrix, depressing the blank into the matrix by use of a reciprocable ram from an upper position at said forming station 15 to a lower position thereat, and acting as follows on the blank while in said matrix, namely, bending-up the wall portions of the blank to form carton walls, bending-in the lateral extensions to form flaps, doubling-down said margins 20 toward the respective walls for adhesive binding, pressing the adhesive-treated components inwardly against the ram while at the end of its working stroke to complete the adhesive action and give permanence of form to the carton, and holding the carton at the lower position during the return stroke of the ram for ejection by the next blank of the matrix for conveyance therefrom.

2. A method of manufacturing a carton from 30 a blank, said blank including side wall portions, lateral extensions and projecting margins thereon and adhesive-treated end wall portions, which method consists in leading-in the blank as one of a series of blanks from an adhesive-treatment 35 station to a matrix at a forming station, depressing the blank into said matrix by use of a reciprocable ram from an upper position at said forming station to a lower position thereat, and acting as follows on the blank while in said 40 matrix, namely, bending-up the side wall portions of the blank in perpendicular relation thereto to form carton side walls, bending-in the lateral extensions of said walls in perpendicular relation thereto to form flaps, bending- 45 up the adhesive-treated end wall portions in perpendicular relation to the blank to engage said flaps and form carton end walls, doubling-down said margins toward the end walls and said flaps for adhesion, pressing the adhesive-treated components inwardly against the ram while at the end of its working stroke to complete the adhesive action and give permanence of form to the carton, and holding the carton at the lower position during the return stroke of the ram for 50 ejection by the next blank of the series out of the matrix for conveyance therefrom.

3. A method as claimed in claim 1 in which opposite wall portions which do not have projecting margins to be doubled-down in the matrix are formed in a preliminary operation with doubled-down adhesively bound margins which, in the finished carton, correspond to the margins doubled-down in the matrix.

4. A method as claimed in claim 1 in which 65 opposite wall portions which do not have projecting margins to be doubled-down in the matrix are formed in a preliminary operation with doubled-down adhesively bound margins which, in the finished carton, correspond to the margins 70 doubled-down in the matrix, in which the margins doubled-down in a preliminary operation have lateral projections, and in which said projections are bound-in along with the lateral extensions so that said projections will be adhe- 75

sively engaged by the margins doubled-down in the matrix and will thus form corner reinforcements.

5. An automatic machine for forming a carton from a blank comprising a ram reciprocable between an upper position and a lower position, a matrix beneath the ram into which the ram works, means extending in one direction in relation to the matrix for bending-up opposite wall portions of the blank, means associated with the matrix and movable laterally in timed relationship with the ram to bend-in lateral extensions on said wall portions, means extending transverse to said direction for bending-up the remaining wall portions of the blank, means movably mounted in relation to the ram for doubling-down projecting margins on certain of the wall portions, and pressure elements which are movable inwardly toward the ram to press against it in its lower position the bent components into permanent adhesive engagement with one another to form a carton, said matrix being adapted to hold the formed carton in the lower position for ejection on the next descent of the ram by the next carton formed.

6. An automatic machine for forming a carton from a blank comprising a ram reciprocable between an upper position and a lower position, a matrix beneath the ram into which the ram works, longitudinally extending ledges above the matrix for bending-up side wall portions of the blank, lateral ledges associated with the matrix and movable laterally in timed relationship with the ram to bend-in lateral extensions on said side wall portions, transversely extending ledges associated with the matrix for bending-up the end wall portions of the blank, transversely extending means movably mounted in relation to the ram for bending-in projecting margins on the end wall portions, means slidably carried by the ram for doubling-down the bent-in projecting margins, and pressure elements which are movable inwardly toward the ram to press

against it in its lower position the end wall portions and doubled-down margins into permanent engagement with the bent-in lateral extensions of the side wall portions to form a carton, said matrix being adapted to hold the formed 5 carton in the lower position for ejection on the next descent of the ram by the next carton formed.

7. An automatic machine as claimed in claim 6 in which the means on the ram for doubling-down the bent-in margins consist of vertically movable slides on the ram, said slides being engageable with said margins, levers fulcrumed in the ram in operative connection with said slides, and cam-operated means for pivoting said levers 10 15 in timed relationship with the ram.

8. An automatic machine for forming a carton from a blank comprising a ram reciprocable between an upper position and a lower position, a matrix beneath the ram into which the ram 20 works, ledges at the top of the matrix to provide a supporting surface for the blank, stationary guide and stop means disposed on said surface to position the blank with respect to the matrix, means extending in one direction in relation to 25 the matrix for bending-up opposite wall portions of the blank, means associated with the matrix and movable laterally in timed relationship with the ram to bend-in lateral extensions on said wall portions, means extending transverse to 30 said direction for bending-up the remaining wall portions of the blank, means movably mounted in relation to the ram for doubling-down projecting margins on certain of the wall portions, and pressure elements which are movable inwardly toward the ram to press against it in its 35 lower position the bent components into permanent adhesive engagement with one another to form a carton, said matrix being adapted to hold the formed carton in the lower position for ejection on the next descent of the ram by the next 40 formed carton.

JOHN HOZA.
